The ornamental design for a shock absorbing lid for containers, as shown and described.

DESCRIPTION

FIG. 1 is a perspective view of the top and one side of a shock absorbing lid for containers showing my new design;

FIG. 2 is a top plan view thereof;

FIG. 3 is a front side elevation view thereof, showing the side shown in FIG. 1, the opposite rear side view being a mirror image thereof;

FIG. 4 is a bottom plan view thereof;

FIG. 5 is a right side view of FIG. 1, the opposite left side being a mirror image thereof;

FIG. 6 is a top plan view of a modified form of my new design, the side elevation views being the same as shown in FIGS. 3 and 5; and,

FIG. 7 is a bottom plan view thereof.

The broken line showing of environmental structure in FIG. 1 is for illustrative purposes only and forms no part of the claimed design.
